James J. Williams

UNITED STATES PATENT OFFICE.

HERMAN L. ANDERSON, OF MINNEAPOLIS, MINNESOTA.

TRESTLE FOR SUPPORTING A SCAFFOLD.

Application filed April 23, 1923. Serial No. 633,847.

To all whom it may concern:

Be it known that I, HERMAN L. ANDERSON, a citizen of the United States, residing at Minneapolis, in the county of Hennepin 5 and State of Minnesota, have invented certain new and useful Improvements in Trestles for Supporting a Scaffold; and I do hereby declare the following to be a full, clear, and exact description of the invention, 10 such as will enable others skilled in the art to which it appertains to make and use the same.

This invention relates to a trestle or jack adapted to support boards or other members 15 forming a scaffold. Such scaffolds are now very commonly used by brick layers, plasterers, painters and other workmen where it is necessary to work on an elevated surface.

20 It is an object of this invention to provide a trestle of very simple and efficient form made of standard material and one which can be collapsed into compact condition for transportation.

25 It is a further object of the invention to construct such a trestle mainly from T-shaped bars and angle bars, which trestle also comprises adjustable legs whereby the height of the trestle may be varied.

30 Among other objects of the invention are the provision of simple and efficient guiding means for the adjustable legs, means for holding the same in adjustable position and provision for holding the parts in collapsed 35 condition.

These and other objects and advantages of the invention will be fully set forth in the following description made in connection with the accompanying drawings in which 40 like reference characters refer to the same parts throughout the different views, and in which,

Fig. 1 is a view in side elevation of the device;

45 Fig. 2 is a view in end elevation thereof; Fig. 3 is a view in side elevation of the parts in collapsed position;

Fig. 4 is a fragmentary section taken on the line 4-4 of Fig. 1;

50 Fig. 5 is a transverse section taken on the line 5-5 of Fig. 1;

Fig. 6 is a transverse section taken on the line 6-6 of Fig. 1; and

55 Fig. 7 is a partial view similar to Fig. 2 shown on an enlarged scale and partly in vertical section.

Referring to the drawings, the device comprises a top supporting member 1 adapted to be disposed in substantially horizontal position and preferably formed of a T-shaped bar, as clearly shown in Fig. 2. Pivotal secured adjacent each end of the bar 1 by headed and nutted bolts extending through the main or vertical member of the T is a pair of diverging members 2. The 65 members 2 are formed of angle bars and are slightly bent at their ends which are connected to the member 1 by headed and nutted bolts 1^a so that one side of the same lies in flat contact with the main or vertical 70 member of the T-shaped member 1. Each of the bars 2 is provided with a series of aligned apertures 3 extending through one of the sides thereof and preferably, as illustrated, the side which is pivotally connected to the bar 1. The members 2 also have secured adjacent their lower ends by rivets, or otherwise, small channel-shaped members 4, as shown in Fig. 6, which channel members are formed to extend over the 75 edges of the members 2 and also to extend over and embrace the edges of leg members 5 also formed of angle bars adapted to fit and slide in the members 2 and having their edges flush with the edges of members 3. 80 The bars 5 are thus guided for sliding movement in the members 2 by the channels 4 and the members 5 have secured thereto adjacent their top edges, small channel members 5^a adapted to extend over and embrace 85 the side edges of the bars 2 and 5. Each of the bars 5 also has secured thereto a spring plate or latch member 6 having projecting from one end thereof a pin 7. The pin 7 extends through a hole in the bar 5 and is 90 adapted to be received in any one of the holes 3 in the bars 2 whereby the members 5 can be secured in various positions longitudinally of the bars 2. The members 2 also have secured thereto adjacent their 95 lower ends the lower ends of angle bars 8 which are pivotally connected at each side of the web or vertical portion of the bar 1 intermediate the ends thereof there being four of said bars 8. These members 8 are 100 preferably connected together and to the member 1 by having one flange cut away adjacent their ends which ends are superposed and receive a headed and nutted bolt 9 passing through member 1 substantially at 105 the center thereof. The ends of members 8 receiving bolt 9 may, if desired, be bent

slightly to lie flat against member 1. Said members 8 have apertures 10 formed through one of the sides thereof adjacent their lower ends. One of the members 2 at each end of the device has pivotally secured thereto an arm 11 having a slot 12 formed therein adjacent one end thereof, thus constituting a hook, which slot is adapted to hook over a bolt 13 projecting from the other member 2 of the pair, which bolt 13 has a head countersunk into one side of the member 2 and is threaded so that the same may be provided with a suitable nut.

When the device is set up for use the same is disposed in the position illustrated in Fig. 1. The members 2 extend downwardly and the respective pairs thereof diverge and are braced by the bar 11, as shown in Fig. 2. The members of the respective pairs also diverge slightly and are braced by the members 11. The leg sections 5 can be adjusted to the desired height and will be guided and kept in close fitting relation to the members 2 by the channel members 4 and 5^a. These leg sections 5 can, as stated, be secured in various positions by means of a spring latch 6 and pin 7. A very strong, durable and simple trestle is thus provided which can be adjusted to various heights.

When it is desired to transport the trestle, the members 8 will be disconnected from the members 2 and from the bolts 13. The latches 6 will be disengaged and the members 5 slid upwardly on the members 2, the pin 7 being engaged in the uppermost hole 3 on the members 2. The nuts on bolts 1^a will now be loosened and the members 2, together with the members 5 will then be swung about their bolts 1^a and brought into parallel relation to the member 1 and disposed so as to lie along the vertical web of the member 1 and in the angles thereof, as shown in Fig. 3. It will be noted, as shown in Fig. 1, that the holes through the members 2 through which bolt 1^a passes are considerably larger than the diameter of said bolt so that the members 2 can be swung into parallel relation with the member 1. The members 8 will now be swung upwardly over the member 2 so as to lie in the angles thereof, and these members will then also be substantially in parallel relation to the member 1. When the members 8 are so positioned, the holes 10 therein will come into alignment with the bolts 1^a, the nuts can now be removed from these bolts and bolts passed through said holes 10 as well as through the members 2 when the nuts can again be placed thereon. All of the mem-

bers will then be held in compact substantially parallel relation, as shown in Fig. 3 and the device will occupy small space so that the same can easily be transported.

From the above description it is seen that applicant has provided an extremely simple, rugged and durable trestle and one which can readily be made from structural iron or steel which is easily procurable. The parts of the device are comparatively few and the device is extremely simple. The device has been amply demonstrated in actual practice and found to be highly efficient for the purpose intended.

It will, of course, be understood, that various changes may be made in the form, details, arrangement and proportions of the parts without departing from the scope of applicant's invention, which, generally stated, consists in a device capable of carrying out the objects above enumerated and such as shown and described and set forth in the appended claims.

What is claimed is:

1. A trestle formed of standard structural steel comprising a horizontally disposed T bar with its central web disposed vertically and downwardly, a pair of supporting angle bars pivotally bolted through said web adjacent each end of said bar and alined at opposite sides thereof, said angle bars being bent outwardly adjacent their pivots to diverge downwardly and being provided with spaced holes through one side thereof, an extension angle bar fitting in and adjustable in each of said angle bars, latching means fitting into said holes to hold the latter bars in adjusted position, means extending between the bars of each pair of first mentioned angle bars, and a pair of bracing angle bars pivoted at each side of said web of said T bar adjacent its central portion the bars of each pair extending downwardly in opposite directions to one of the first mentioned angle bars and pivotally secured thereto, said bracing bars being adapted to be disconnected at one end and collapsed into close fitting relation with said T bar and with the supporting and extension angle bars when the trestle is in folded condition.

2. The structure set forth in claim 1, said last mentioned angle bars having holes therein adapted to receive the bolts connecting the first mentioned angle bars to the T-bar when the trestle is in collapsed condition.

In testimony whereof I affix my signature.

HERMAN L. ANDERSON.
